CLAIM

The ornamental design for a bottle opener, as shown and described.

DESCRIPTION

FIG. 1 is a front isometric view of a bottle opener showing our new design;

FIG. 2 is a rear isometric view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The dot-dash broken lines throughout the drawings represent a boundary of the claimed design. The dash-dash broken lines throughout the drawing figures depict portions of the bottle opener that form no part of the claimed design. The broken lines and unshaded surfaces bounded by broken lines form no part of the claimed design.
